UNITED STATES PATENT OFFICE.

WILLIAM HOGE, OF YOUNGSTOWN, OHIO, ASSIGNOR TO THE GENERAL FIREPROOFING COMPANY, OF YOUNGSTOWN, OHIO, A CORPORATION OF OHIO.

INDEX SYSTEM FOR CARDS AND THE LIKE.

Application filed September 29, 1926. Serial No. 138,480.

This invention relates to an indexing system for assisting in the filing and locating of classified information such as record cards, files, different subjects in bound books and the like.

To that end the invention contemplates a system which is primarily a numerical index wherein the numerical references predominate, thereby greatly facilitating filing and location of subject matter and insuring accuracy. While the invention uses a combination of numerals and parts of the alphabet, nevertheless the alphabetical feature is subsidiary because the letters of the alphabet are intended merely to serve the purpose of directing the operator to the section of the file desired to locate the name, file, or subject matter searched for.

Another object of the invention is to provide an indexing system which when used in connection with the filing of cards may be made in standard sets of minimum size capable of being readily expanded as the size of the file increases by using additional standard units as distinguished from the utilization of special guides having individual values such for instance as is done in some systems now in use.

A further and more specific object of the invention is to provide in combination with the guide card having thereon the main letter of the alphabet, a pilot guide omitting the first letter of the name as well as the vowels a, e, i, o, u and y and the consonants h and w, no key or code letters and no sounds or words or portions thereof being used to determine the location of the name searched for. In that connection the function of the pilot guide resembles that of the key board of a typewriter, and the spelling of the name is carried to the first, second or third additional consonant, depending upon the size of the known arrangement of the guides located behind the pilot guide. Thus, the present system contemplates a numerical system of locating and identifying cards by a letter of the alphabet and a series of numerals.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which

Figure 1 is a diagrammatic plan view illustrating the application of the invention. 60

Figure 2 is a view illustrating the combination of the master guide with the pilot and a major numerical card.

Figure 3 is a view similar to Fig. 2 showing the addition of an intermediate numerical card to the combination of Figure 2.

Figure 4 is a view similar to Fig. 3 showing the addition of one of the minor numerical cards to the combination of Fig. 3.

Figure 5 is a view illustrating the addition to Fig. 4 of one of the given name or initial cards.

Similar reference characters designate corresponding parts throughout the several figures of the drawings.

In carrying the invention into effect it is proposed to provide units or sections corresponding to the various letters of the alphabet, the said units each including a master guide A having thereon the letter of the alphabet; a pilot guide B, and a series of major numerical guides C, a series of intermediate numerical cards D together with a plurality of minor numerical guides E which in turn may cooperate with given name or initial guides F.

The master guide A is preferably tabbed in the first position to designate the first, first two, or the first three letters of the name depending upon the size of the index required for a given list of names. In the example shown the master guide card A is provided with the indexing letter "B" of the alphabet, and in an index of the type illustrated there will be as many master guide cards as there are letters of the alphabet, although it will of course be understood that the number of master guides can be increased when more than the first letter of the alphabet is employed.

Immediately behind each master guide A is the broad-tab guide B which constitutes the pilot or reference guide since it bears the primary classification data for the system. The tab of this guide preferably extends substantially all the way across the top thereof and is divided into six spaces by the printed rules 1, thereby providing six sections or spaces for receiving reference data. As previously indicated eight of the 110

- twenty-six letters of the alphabet are eliminated by avoiding the use of the six vowels and the consonants h and w. The remaining eighteen consonants are grouped into six 5 divisions in combination with a numeral corresponding to each division, the manner of grouping being suggested by the way that the various consonants are uttered, or each group comprising those that have substantially similar sounds. By grouping the letters into six divisions, those having the similarities mentioned may be readily grouped to assist in the filing and location of names spelled differently but pronounced alike. 10
- Thus, the pilot or reference guide B contains six divisions or groups of consonants of the alphabet, numbered serially, and the consonants acting as a spelling guide. 15
- Behind each pilot guide there is provided a series of major, intermediate and minor numerical guides as well as a series of given-name guides, the same being respectively designated as C, D, E and F. Thus, there 20 are three numerical units and one combination numeral and letter unit. The first numerical unit consists of seven guides numbered from "0" in multiples of 1000 up to 6000. The second or intermediate unit consists of six guide cards numbered in multiples 25 of one hundred from 100 to 600, and the third or minor numerical unit consists of six guides numbered in multiples of ten from 10 to 60. The fourth combination numerical and letter unit, called the given name or initial unit includes nine cards (four of 30 which are shown) having the letters of the alphabet distributed thereon. One or more of these units appear behind each pilot guide regardless of the size or the length of names 35 to be indexed and as they are standard in every index, the indexing is simplified. The operator soon becomes so familiar with them that reference becomes automatic and instantaneous. 40
- The guides of the section F will be used for sub-indexing cards behind the numerical guides according to given names, first initials or second names and are provided to give a further means of indexing a particular numerically identified section. 45

From the foregoing it will be apparent that the present invention provides a system in which the numerical features predominate. Fig. 2 illustrates the combination of 50 a master guide and a pilot guide with one of the major numerical guides which will provide for locating a name having a consonant falling under the first section. If the name had two consonants falling under the first 55 section on the pilot card, the card bearing such name would be classified behind the intermediate numerical card 100 as shown in Fig. 3. If the cards filed behind the intermediate numerical 100 guide D are desired 60 to be further classified, the minor numerical

cards E may be added as shown in Fig. 4. These guides E are preferably tabbed in the fourth position, and the cards behind them may be further sub-divided by using the given-name cards F as shown in Fig. 5. 70

In using the index the name to be found or filed is analyzed and identified by the data on the pilot card B, and then filed accordingly.

For example, referring to Fig. 5, suppose 75 that it is desired to file or locate a card bearing the name "Babson, G. R.", the first step is to locate the section of the file by means of the master guide A. In this case it would be the master card having the 80 letter of the alphabet B thereon. The first consonant following the notation on the master guide is then located on the pilot guide B and the number of the section on the pilot guide in which this consonant appears 85 gives the first or major numerical guide behind which the name may be found. Thus, in the illustration given "b" being the first consonant, the card bearing the name "Babson, G. R." would be located behind major numerical guide 1000 and if 90 there is a congestion behind this guide large enough to use a set of intermediate numerical guides the name would be behind the minor numerical guide 200 located behind major numerical guide 1000. Then if there 95 is a set of minor numerical cards behind the intermediate card 200 the card of "Babson" would go behind the minor card numbered 50. 100

In locating the name "Babson, G. R." the master guide "B" would show the section of the file in which the name is located and as "B" and "a" play no further part in the search, the first consonant "b" would show 105 that 1000 is the first numerical guide (determined by referring to the pilot guide) and the second consonant "s" would indicate the 200 intermediate numerical guide. If there 110 is a congestion behind the intermediate guide 200 that necessitates further indexing the minor numerical cards are brought into use as above explained and if it is desired to classify the card according to the given name or initials a set of given name guides 115 would be used and the card bearing the name "Babson, G. R." would be located behind given name guide 4 G-H. The identification number for the card would then be B-1254. This number would appear on 120 the card so that refiling would be done entirely by number. This makes the refiling 125 quicker and more accurate.

In connection with the major numerical cards C it is to be noted that it was previously mentioned that seven major numerical cards were used while only six intermediate and six numerical cards were used. In explanation of that it may be pointed out that 130 cards bearing names having names thereon

including only vowels or vowels and consonants H and W may be placed behind the card bearing the naught or "0", and in front of the 1000 card. For instance, the name "Bay" having the vowel "a" and the vowel "y" would not fall under any of the six divisions on the pilot guide card B, and therefore it would be classified under the "0" card of the major numerical card unit.

10 A card bearing the name "Bay" therefore would bear the code designation B—O.

Also with the four sets of cards, namely the major, intermediate and minor numerical cards, and the given name cards, it will be apparent that the present system provides a perfect numerical unit wherein the given name cards constitute the "units," the minor numerical cards constitute the "tens," the intermediate numerical cards constitute the "hundreds" and the major numerical cards constitute the "thousands." It will therefore be apparent that the possibilities of expansion by this system are unlimited, and in systems wherein a million or more cards 25 are to be classified the present novel arrangement is particularly helpful in the quick and accurate location and filing of cards.

From the foregoing it is thought that the features and advantages of the invention 30 will be readily apparent. The index is especially adapted to large record lists of names and in addition to being simple to manufacture, install and operate, permits of unlimited expansion. It will never be necessary to discard any guide because when one 35 guide of a section ceases to function it can be moved to another section.

Without further description it is thought that the features and advantages of the invention 40 will be readily apparent to those skilled in the art, and it will of course be understood that changes in the form, proportion and minor details of construction may be resorted to, without departing from 45 the spirit of the invention and scope of the appended claims.

I claim:

1. An index system for numerically classifying subject matter, including a master index element and a pilot index element having thereon certain pilot letters of the alphabet identified with numerals, and a plurality of numerical indices related to the numerals on the pilot card in accordance 55 with the numerical order of pilot letters in the given word.

2. An index system including a master guide card having an alphabetical designation, a pilot guide in juxtaposition to the master guide and provided with a plurality of indexing spaces, each of which spaces is numbered and also contains consonants grouped as a spelling guide, and numerical guides containing numerical designations related to the numbered spaces on the pilot 65

card and occupying a position behind said pilot card.

3. An index system including a master guide card having an alphabetical designation, a pilot guide in juxtaposition to the master guide and provided with a plurality of indexing spaces, each of which spaces is numbered and contains consonants grouped as a spelling guide, and a major numerical guide having thereon numerical designations related to the numbered spaces of the pilot card and occupying a position behind the same.

4. A card index system including in combination with a master guide card having thereon an alphabetical symbol and numerical guide cards having numerical symbols, of a pilot guide card arranged between the master guide card and the numerical guide cards and bearing thereon combined numerical and letter designations grouped as a spelling guide, said numerical designations being related to the numerical symbols of the numerical guide cards.

5. In a card index system the combination with a guide card having a tab containing a letter of the alphabet and numerical guide cards having tabs containing numerical symbols, of a pilot guide card between the master guide card and the numerical guide cards and provided with an indexing tab extending substantially its full length and provided with a plurality of spaces each of which contains a numerical designation and a certain consonant designation or designations forming a spelling guide, the numerical and consonant designations on the pilot card being coordinated respectively with the designations on the numerical cards.

6. An index system including a master guide card having a letter of the alphabet thereon, a pilot guide in juxtaposition to the master guide and provided with a plurality of indexing spaces, each of which spaces is numbered and contains one or more consonants grouped as spelling guides, a major numerical guide having thereon a numerical designation related to one of the numbered spaces on the pilot guide and occupying a position behind the pilot guide, 115 and a plurality of series of numerical guides arranged behind the major numerical guide and having thereon numerical designations related to the numbered spaces on the pilot guide.

7. An index system including a master guide card having a letter of the alphabet thereon, a pilot guide in juxtaposition to the master guide and provided with a plurality of indexing spaces, each of which spaces is numbered and contains one or more consonants grouped as a spelling guide, a major numerical guide having thereon a numerical designation related to one of the numbered spaces on the pilot guide and oc-

cupying a position behind the pilot guide, an intermediate numerical guide arranged behind the major numerical guide and having thereon a numerical designation related 5 to one of the numbered spaces on the pilot guide, a minor numerical guide arranged behind the intermediate numerical guide and a given name or initial guide arranged behind the minor numerical guide and having 10 both numerical and alphabet designations.

8. A card index system including a master guide card having a projecting tab provided with an alphabetic designation, a pilot 15 guide card arranged in juxtaposition to the master guide card and having a tab extending approximately the full length thereof, a plurality of indexing spaces formed on the tab of the pilot card and each space having 20 therein a numeral and one or more consonants of the alphabet grouped as a spelling guide, and a plurality of cards having projecting tabs arranged in different positions and each bearing a numerical designation 25 relating to the numbered spaces on the pilot card.

9. A card index system including a master guide card having an alphabetical designation, a pilot guide card in juxtaposition to 30 the master guide card and provided with indexing spaces, each of which spaces is numbered and contains one or more letters grouped as a spelling guide, and a plurality of major, intermediate and minor numerical 35 guide cards arranged behind the pilot card, there being as many of each of the intermediate and minor numerical guide cards as there are divisions on the pilot card, and each of said intermediate and 40 minor numerical cards bearing a numerical designation related to the numbered spaces on the pilot card.

10. A card index system including a master guide card having an alphabetical 45 designation, a pilot guide card in juxtaposition to the master guide card and provided with indexing spaces, each of which spaces is numbered and contains one or more letters grouped as a spelling guide, and a 50 plurality of major and minor numerical guide cards arranged behind the pilot card, there being one more major and as many of each of the intermediate and minor numerical 55 guide cards as there are divisions on the pilot card, each of said major, intermediate and minor numerical cards bearing a

numerical designation related to the numbered spaces on the pilot card, and a series of given name or initial cards adapted to be used behind one of the minor numerical 60 cards and bearing thereon numerals in sub-multiples of ten below the numerical designations of the minor numerical cards and also bearing serially related letters of the 65 alphabet.

11. An index system including a master guide card having an alphabetical designation, a pilot guide card in juxtaposition to the master guide card and provided with indexing spaces, each of which spaces is 70 numbered and contains one or more letters grouped as a spelling guide, and a series of seven major numerical guide cards located behind the pilot card to provide six classification divisions numerically related to the 75 numbers on the pilot card and the seventh card providing a guide for indexing words having vowels and consonants not scheduled on the pilot card.

12. An index system including a master guide card having alphabetical designations, a pilot guide in juxtaposition to the master guide and provided with a plurality of indexing spaces, each of which spaces is numbered and contains one or more letters 80 grouped to provide a spelling guide, and a plurality of numerical guide card units arranged behind the pilot card, said guide cards being tabbed in four positions corresponding to "units", "tens", "hundreds" and 85 "thousands" and bearing numbers numerically related to the numbers on the pilot card.

13. An index system including a master guide card having an alphabetical designation, a pilot guide card in juxtaposition to the master guide card and provided with a plurality of indexing spaces, each of which spaces is numbered and contains one or more letters grouped to provide a spelling 95 guide, a plurality of numerical guide units arranged behind the pilot guide card, one of said units containing one more card than the number of spaces on the pilot card, and another of said units containing cards having thereon combined numeral and letter 100 designations, and the remainder of said units containing as many guide cards as there are spaces on the pilot card.

In testimony whereof I hereunto affix my 110 signature.

WILLIAM HOGE.
